UNITED STATES PATENT OFFICE.

CHESTER L. WILLIAMS, OF CHAPIN, ILLINOIS.

GATE-HINGE.

1,349,797.

Specification of Letters Patent. Patented Aug. 17, 1920.

Application filed November 24, 1919. Serial No. 340,087.

To all whom it may concern:

Be it known that I, CHESTER L. WILLIAMS, a citizen of the United States, residing at Chapin, in the county of Morgan and State 5 of Illinois, have invented certain new and useful Improvements in Gate-Hinges; and I do declare the following to be a full, clear, and exact description of the invention, such as will enable others skilled in the art to 10 which it appertains to make and use the same.

This invention relates to improvements in gate hinges, and it has more particular reference to a farm gate hinge, although it is 15 not to be restricted to such use.

The principal object of the invention is to provide a hinge which is exceedingly simple in construction, inexpensive to manufacture, yet highly efficient in use, the construction being such that it can be adjusted to posts of various diameters, and when in position on the posts, may be moved vertically thereon to any desired point by simply loosening the bolt which holds it in position 25 on the posts.

Other objects and advantages may become apparent during the course of the following description.

In the accompanying drawing forming a 30 part of this specification and in which like numerals are employed to designate like parts throughout the same,

Figure 1 is a side elevation of a portion of a gate and its post illustrating the application of my device.

Fig. 2 is a transverse section on the plane of the line 2--2 of Fig. 1.

Fig. 3 is an enlarged detail perspective view of the post engaging plate.

In the drawing, wherein for the purpose of illustration is shown a preferred embodiment of my invention, the letter P designates a post to which my improved device is fastened and the letter G designates the 45 gate which it serves to support.

As both of the devices are alike and as each one is of the same construction, I will describe only one of them, it being understood that while portions of the description 50 appear in the singular it is intended to cover all like parts.

My invention resides in the provision of a substantially flexible member which surrounds the post P. The device consists 55 mainly of three parts, viz; an attaching plate 1, a plurality of filling links 2, and a

pair of substantially L-shaped plates or connecting link 3. Plate 1 is made of metal and is reduced in width at its opposite ends to provide a pair of relatively wide hooks 4, 60 the purpose of which will hereinafter be set forth. In addition to the hooks 4 this plate is also provided at the center of its lower edge with a depending tongue 5 which bears against the post P and acts as a brace, thereby preventing sagging of the gate. Cast integral with, or secured to the plate in any other suitable manner, is a pintle 6 which co-acts with the hinge member 7 carried by the gate, and permits the gate to revolve 70 thereon, as is obvious. If desired this pintle 6 may be provided with a shoulder 8 to form a bearing for the hinge members 7. As before stated, the device includes a series of links 2 which in this instance are merely 75 in the form of sprocket chain links, and each link is made of malleable iron and is provided at one of its ends with a relatively wide hook 9 which engages another link of the series. This construction will permit 80 the links to be readily detached for the removal or insertion of other links to adapt the device to posts of various diameters. In use, any number of links may be employed according to the diameter of the posts to 85 which they are attached. Two of these links 2 are connected at one of their ends to the hooks 4 of the attaching plate 1, and, as before stated, the opposite hooked ends thereof engage another link of the series. 90

In order to secure the free ends of the end links together I employ a pair of L-shaped slotted connecting plates 3 and the hooks 9 of the links 2 are received in said slots. When in position on the post the L-shaped plates 95 are secured together by means of a bolt 10 which extends through the apertures formed at one end thereof. With the above construction it will be seen that a chain-like structure will be had, and the particular advantage of this construction is that the device will conform to the shape of the post more so than if all the parts were rigidly connected together, thereby adapting the device for use on posts of different shapes. 100 All of the parts are so constructed that they may be readily detached from one another thereby permitting the device to set for use on posts of different diameters. When the device is in position on the post and it is 105 desired to move it vertically thereon it will be only necessary to loosen the bolt 10 there-

- by permitting the device to be readily moved to the desired point, and then by tightening the bolt again the device will be clamped tightly in position. One of the 5 main features of the invention, and one of the points which I desire to emphasize is the fact that the plate 1 is so constructed that it will prevent sagging of the gate to any great extent. This is due to the fact 10 that it is provided with the depending tongue 5 which bears against the post and serves to brace the plate, and in turn prevents sagging of the gate which is carried thereby.
- 15 The manner of using and assembling my device is thought to be obvious from the foregoing description, a further description is therefore deemed unnecessary.
- With the device of the above mentioned 20 type it will be seen that it is not necessary to employ nails or bolts to fasten it to the post thereby preventing formation of holes in the posts which might weaken the posts and also detract from the appearance of 25 the post.

I claim:

A gate hinge comprising a flat metal hinge carrying plate having its opposite ends reduced in width and bent to form relatively wide hooks and being provided 30 at the center of its bottom edge with a depending tongue to bear against the post and prevent possible sagging of the gate, a pair of rectangular open links made of malleable iron and having one of their ends disposed 35 in said hooks, each link being provided at its opposite end with a hook of the same width as the first named hooks, additional rectangular open links attached to the second named hooks, these links being likewise 40 provided at their opposite ends with like hooks, a pair of L-shaped connecting plates, each having a slot at one end for reception of one of the last named hooks and being apertured at their opposite ends, and a bolt 45 passing through said apertures to retain the connecting plates together.

In testimony whereof I have hereunto set my hand.

CHESTER L. WILLIAMS.
